United States Patent Office

Des. 202,921
Patented Nov. 16, 1965

202,921

STAMP DISPENSER

Richard A. Hughes, Minneapolis, Minn., assignor to Hughes Corporation, Minneapolis, Minn., a corporation of Minnesota

Filed Sept. 10, 1964, Ser. No. 81,671

Term of patent 14 years

(Cl. D52—3)

FIG. 1

FIG. 2

FIG. 3

FIGURE 1 is a front perspective view of a stamp dispenser, showing my new design.

FIGURE 2 is a perspective view, on a reduced scale,
of the rear of the dispenser.

FIGURE 3 is a side elevational view thereof.

I claim:

The ornamental design for a stamp dispenser, substantially as shown.

References Cited by the Examiner

UNITED STATES PATENTS

2,601,062	6/1952	Singer	-----	312—39
2,712,442	7/1955	Hanson
3,087,646	4/1963	Ruby	-----	312—39

WALLACE R. BURKE, Primary Examiner.